E. I. DODDS,
STAYBOLT STRUCTURE,
APPLICATION FILED AUG. 29, 1919.

1,354,600.

Patented Oct. 5, 1920.

E. I. DODDS, INVENTOR
By Seymour Bright, Attorneys

UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAYBOLT STRUCTURE.

1,354,600.

Specification of Letters Patent. Patented Oct. 5, 1920.

Application filed August 29, 1919. Serial No. 320,729.

To all whom it may concern:

Be it known that I, ETHAN I. DODDS, a citizen of the United States, and a resident of Pittsburgh, in the county of Allegheny and State of Pennsylvania, have invented certain new and useful Improvements in Staybolt Structures; and I do hereby declare the following to be a full, clear, and exact description of the invention, such as will enable others skilled in the art to which it appertains to make and use the same.

This invention relates to improvements in staybolt structures for boilers,—one object of the invention being to provide a mounting for the headed end of a staybolt at the outer boiler sheet, which will become so disposed as to insure correct alinement of the staybolt with its points of connection with the respective boiler sheets, and which shall be capable of a wide range of adjustment.

A further object is to provide a structure having the characteristics above specified and yet avoid the necessity of rounding or curving either the bearing sleeve or bushing or the wall of the opening in the boiler sheet which receives the sleeve or bushing.

With these and other objects in view, the invention consists in certain novel features of construction and combinations of parts as hereinafter set forth and pointed out in the claims.

In the accompanying drawings; Figure 1 is a sectional view showing an embodiment of my invention; Fig. 2 is a view partly in elevation showing the bearing sleeve and bolt having their axes at an angle to the axis of the opening in the boiler sheet, and Fig. 3 is a sectional view showing a modification.

1 represents the outer sheet and 2 the inner sheet of a boiler.

The outer sheet is provided with openings 3 to accommodate the mounting of the headed ends 4^a of staybolts, such as shown at 4, and the inner ends of the latter are secured to the inner boiler sheet in any suitable manner.

The bolts opening 3 in the outer boiler sheet is made straight transversely of the sheet and is uniform in diameter substantially from the outer to the inner face of the sheet.

A conical or tapering bearing sleeve or bushing 5, having a straight outer face lengthwise of the same, enters the opening

and its tapering external wall has a universally movable mounting, between its ends against the outer end of the wall of the opening 3 in the boiler sheet when said sleeve or bushing is so disposed that its axis shall be approximately coincident with the axis of the opening 3, as shown in Fig. 1. The sleeve or bushing may, however be so disposed that its axis may be at a decided angle to the axis of the opening as shown in Fig. 2,—in which event, a portion of the inner end of the sleeve may engage or approximate the wall of the opening 3.

The bearing sleeve or bushing is provided interiorly with a seat 6 for the head 4^a of the staybolt 4 and the larger outer end of said sleeve or bushing may be threaded internally for the reception of the threaded portion of a plug or closure 7.

In the construction shown in Fig. 3, the wall of the opening is made somewhat tapering, as at 8.

My improvement will permit a wide range of adjustment of the bearing sleeve or bushing, so that the staybolt which has its head mounted therein, may readily accommodate itself to its points of connection with the respective boiler sheets, and thus the correct alinement of the staybolt with the points of connection to the respective boiler sheets, will be insured whether the two sheets be parallel or at an angle to each other.

When the bearing sleeve or bushing shall have become properly adjusted to insure correct alinement of the staybolt, it will be secured to the boiler sheet with the use of a weld 9 which may be applied around the sleeve or bushing so that the sleeve or bushing and the boiler sheet will be integrally united.

By the term "transversely of the sheet" is meant, in a direction extending from one face of the sheet toward the other.

Having fully described my invention what I claim as new and desire to secure by Letters-Patent, is:—

1. In a staybolt structure, the combination with a boiler sheet having an opening, the wall of which is straight transversely of the sheet, of a tapering sleeve or bushing entering said opening and having initial universally movable mounting on the boiler sheet at the outer end of said opening, and a

staybolt having a head mounted in said sleeve or bushing.

2. In a staybolt structure, the combination with a boiler sheet provided with an opening having a uniform diameter approximately from the outer to the inner face of the sheet, of a tapering sleeve or bushing entering said opening and having a straight outer face engaging the boiler sheet at one end of said opening, and a staybolt having a head mounted in said tapering sleeve or bushing.
3. In a staybolt structure, the combination with a boiler sheet provided with an opening, a tapering sleeve or bushing entering said opening and having initial universally movable engagement with the boiler sheet, a staybolt having a head mounted in said sleeve or bushing.
4. In a staybolt structure, the combination with a boiler sheet provided with an opening having a uniform diameter approximately from the outer to the inner face of the sheet, of a tapering sleeve or bushing entering said opening and having initial universally movable engagement with the boiler sheet, a staybolt having a head mounted in said sleeve or bushing, and a weld surrounding said sleeve or bushing and integrally uniting the same to the boiler sheet.

sleeve or bushing, and a weld securing said sleeve or bushing to the boiler sheet.

4. In a staybolt structure, the combination with a boiler sheet provided with an opening having a uniform diameter approximately from the outer to the inner face of the sheet, of a tapering sleeve or bushing entering said opening and having initial universally movable engagement with the boiler sheet, a staybolt having a head mounted in said sleeve or bushing, and a weld surrounding said sleeve or bushing and integrally uniting the same to the boiler sheet.

In testimony whereof I have signed this specification.

ETHAN L. DODDS.
